MINING MACHINE

Morris P. Holmes, Claremont, N. H., assignor to
 Sullivan Machinery Company, a corporation of
 Massachusetts

Application June 18, 1935, Serial No. 27,214

13 Claims. (Cl. 262—28)

This invention relates to mining machines, and more particularly has reference to coal mining machines having improved adjustable kerf cutting mechanism and improved kerf cutter adjusting and driving means.

An object of this invention is to provide an improved coal mining machine. Another object is to provide an improved coal mining machine having improved adjustable kerf cutting mechanism. A further object is to provide an improved adjustable supporting structure for the kerf cutting mechanism for adjusting the kerf cutter into different elevated positions and having associated therewith improved parallel motion means for maintaining automatically the kerf cutter in a horizontal cutting position during adjustment thereof, and having embodied therein improved means for tilting the kerf cutter through a wide range of angularly related cutting planes with respect to the horizontal. A further object is to provide an improved swinging arm structure and associated parallel motion means for moving the kerf cutter into different elevated positions through a series of parallel horizontal planes, the improved parallel motion means having embodied therein improved means for tilting the kerf cutter through a wide range of angularly related cutting planes with respect to the horizontal. Yet another object is to provide an improved adjustable kerf cutting mechanism for a coal mining machine of the flexibly fed, floor cutter type mounted to slide on its own bottom over the mine floor during the cutting operation. Yet another object is to provide an improved adjustable kerf cutting mechanism having embodied therein improved means for adjusting the kerf cutter into a vertical shearing position with respect to the swinging arm structure at either side of the arm structure and into horizontal cutting positions above and below the arm structure. A still further object of this invention is to provide an improved adjustable supporting structure for the kerf cutting mechanism of the vertical shear cutter type, together with improved feeding and driving means for the kerf cutter. These and other objects and advantages of the invention will, however, hereinafter more fully appear.

In the accompanying drawings there are shown for purposes of illustration three forms which the invention may assume in practice.

In these drawings—

Fig. 1 is a plan view of one illustrative form of the improved mining machine, parts being shown in horizontal section to illustrate structural details.

Fig. 2 is a side elevational view of the machine shown in Fig. 1, a portion of the arm structure being broken away to show the interior construction.

Fig. 3 is an enlarged cross sectional view taken substantially on line 3—3 of Fig. 1.

Fig. 15 is a view similar to Fig. 1 showing another modified form of construction.

Fig. 16 is an enlarged cross sectional view taken on line 16—16 of Fig. 15.

Fig. 17 is a detail view in longitudinal section taken substantially on line 17—17 of Fig. 15.

Fig. 18 is a side elevational view of the mining machine shown in Fig. 15, with parts shown in section.

Fig. 19 is an enlarged view in longitudinal section taken substantially on line 19—19 of Fig. 15.

In the illustrative embodiment of the invention in Figs. 1 to 11, inclusive, there is shown a coal mining machine of the flexibly fed, floor cutter type particularly designed to use in accordance with the room and pillar system of mining. It will be evident, however, that the various novel features of the invention may be embodied in mining machines of various other types. The improved machine comprises a machine frame 1 having a smooth bottom surface 2 whereby the machine may rest upon and slide in any direction over the mine floor. Straddling the forward

35

40

45

50

55

portion of the machine frame and pivotally mounted thereon to swing in a vertical direction with respect thereto is an elongated rigid arm structure 3 on the forward extremity of which is tiltably mounted for rocking movement about a transverse axis parallel with the arm pivot axis, a cutter support 4 by which is carried an elongated plane kerf cutter 5. Associated with the swinging arm structure 3 and tilttable cutter support 4 is an improved "parallel motion" mechanism for tilting the cutter support about its pivot as the arm structure is swung vertically, thereby always to maintain automatically the kerf cutter in a horizontal cutting position during elevation thereof and having embodied therein improved means for tilting the cutter support 4 with respect to the arm structure to tilt the kerf cutter through a wide range of angularly related cutting planes with respect to the horizontal. The machine may be fed over the mine floor by flexible feeding means including relatively rotatable feeding and controlling drums 6 and 7 co-operating respectively with feeding and controlling cables 8 and 9, the drums arranged in coaxial relation at opposite sides of the machine frame on horizontal axes extending transversely of the machine frame at the rear of the pivotal axis of the arm structure, as shown in Figs. 1 and 2. Arranged on vertical axes at the rear end of the machine frame are horizontal guide rolls 10, 10 and 11, 11, while arranged in coaxial relation on horizontal axes extending transversely of the machine frame at opposite sides of the machine frame adjacent the drums are vertical guide rolls 12, 12. Arranged slightly in advance of the guide rolls 12, 12 on relatively inclined axes are vertical guide rolls 13. Located at the opposite front corners of the machine frame are swing arms carrying horizontal guide rolls 14, 14. These guide rolls guide the feeding and controlling cables 8 and 9 in various manners during operation of the machine as is well understood by those skilled in the art. The machine may be fed longitudinally over the mine floor to sump the kerf cutter within the coal seam and may be fed transversely across the coal face to effect a transverse cutting operation, and the arm structure and cutter support may be swung about their respective pivots to move the kerf cutter into various cutting planes at different elevations between the mine roof and mine floor, as will hereinafter be described. If desired, the machine may be fed rectilinearly relative to a bottom skid plate and a hydraulic "walking jack" structure may be employed in conjunction with the skid plate for moving the machine over the mine floor, in the manner described in a copending application to Joseph F. Joy, Serial No. 684,707, filed August 11, 1933, now matured into Patent No. 2,062,657, patented Dec. 1, 1936.

In this illustrative embodiment of the invention, the machine frame supports a motor 15 having its power shaft 16 horizontally disposed and extending longitudinally of the machine, the motor casing overlying the forward portion of the machine frame in the manner shown in Figs. 1 and 2. The arm structure 3 straddles the casing of this motor and has parallel side arm portions 17 and 18, herein preferably made hollow, extending longitudinally along the sides of the frame and having at their rearward ends cylindrical bearing portions 19 journaled on lateral trunnions 20, 20 (see Fig. 3) formed integral with the sides of the machine frame. The cutter support 4 has lateral trunnions 21 journaled in

cylindrical bearing portions 22 formed on the forward extremities of the side arm portions 17 and 18, the support trunnions having flanges 23 with which cooperate retaining rings 24 secured to the bearing portions 22 for retaining the support trunnions within their journal bearings on the outer extremity of the arm structure. The means for elevating and depressing the arm structure 3 with respect to the machine frame comprises a pair of hydraulic cylinders 25 arranged at the opposite sides of the machine frame longitudinally along the opposite sides of the motor casing and located beneath the side arm portions of the arm structure. The lower ends of these cylinders are pivotally mounted at 26 on brackets 27 secured to the machine frame and each contains a reciprocating piston 28 having a forwardly extending piston rod 29. The piston rods extend forwardly through the packed front heads 30 of the cylinders and are pivotally connected at 31 within projecting lugs 32 formed on the side arm portions of the arm structure. When hydraulic pressure is supplied in a suitable manner to the cylinders 25, the pistons 28 may be moved to swing the arm structure to move the kerf cutter into the desired elevated position, and by trapping the pressure within the cylinders the arm structure may be locked in any desired adjusted position about its pivotal axis. Now referring to the improved driving means for the kerf cutter, it will be noted that keyed to the rear end of the motor power shaft 16 is a bevel pinion 35 meshing with a bevel gear 36 (see Figs. 1 and 3). This bevel gear has its hub journaled within the machine frame and is keyed to a horizontal shaft 37 likewise journaled within the machine frame and arranged with its axis alined with the pivotal axis of the arm structure 3. The shaft 37 is connectible by a sliding gear clutch 38 to an alined shaft 39 journaled within bearings supported within the trunnion 20 of the pivotal mounting for the arm structure. The clutch 38 is operated by a shipper lever 40 having a suitable operating handle 41. Keyed to the outer end of the shaft 39 is a double chain sprocket 42 which engages and drives a roller chain 43 of the double strand type arranged within the hollow side arm portion 18 of the arm structure. Secured within the side arm portion 18 within the lower portion thereof is a wear plate 44 for guiding the lower strand of the roller chain 43. The chain 43 engages and drives a double sprocket 45 keyed to a shaft 46 journaled within the cutter support trunnion 21 and arranged with its axis alined with the pivotal axis of the cutter support 4. Keyed to and driven by the shaft 46 is a bevel gear 47 meshing with a bevel gear 48 (see Fig. 6). The hub of the gear 48 is yieldably connected by a disc clutch 49 to a shaft 50 journaled in the cutter support, and this clutch is set at a predetermined load and is adapted to slip automatically upon overload of the kerf cutting mechanism. Keyed to the shaft 50 is a chain sprocket 51 which engages and drives an endless cutter chain 52 guided about the margin of an elongated plane cutter bar 53. The cutter bar 53 is supported by a hanger frame 54 rigidly bolted to the frame of the cutter support 4. Journaled within a bearing sleeve 55 supported within the trunnion for the side arm portion 17 of the arm structure is a shaft 56 having keyed thereto a chain sprocket 57. This chain sprocket is connected by an endless "parallel motion" chain 58 arranged within the hollow arm portion 17 and engaging a chain sprocket 59 keyed to a shaft 60

arranged with its axis alined with the pivotal axis of the cutter support 4 and keyed within the cutter support trunnion 21, as shown in Fig. 1. The shaft 56, as shown in Figs. 3 and 4, has an integral depending arm 62 pivotally connected at 63 to a link 64 in turn pivotally connected at 65 to one end of a lever 66. The lever 66 is pivotally mounted at 67 within the machine frame and has its opposite end pivotally connected at 68 to the lower end of a piston rod 69. Pivotally mounted within horizontal trunnion bearings 70 formed within the machine frame is a servo-motor including a hydraulic cylinder 71 containing a reciprocating piston 72 having its piston rod 69 extending downwardly through the packed lower head 73 of the cylinder. When hydraulic pressure is locked or trapped within the cylinder 71 the chain sprocket 57 is held stationary, and as the arm structure 3 is swung vertically about its pivotal axis with respect to the machine frame, the endless chain 58 engaging the chain sprocket 59 fixed to the cutter support 4 acts automatically to always maintain the kerf cutter in a horizontal cutting position during swinging of the arm structure. When hydraulic pressure is suitably supplied to one end or the other of the cylinder 71 to effect reciprocating motion of the piston 72, the arm 62 may be swung through the lever and link connection to rotate the sprocket 57, thereby to effect through the endless chain 58 and sprocket 59 tilting of the cutter support 4 about its pivotal axis with respect to the arm structure. By locking or trapping the pressure fluid within the cylinder 71 the cutter support may be locked in any position on its pivotal axis. It is accordingly evident that the top and bottom strands of the endless chain 58 form a "parallel motion" mechanism for always maintaining the kerf cutter in a horizontal cutting position during swinging of the arm structure and that the associated means including the cylinder and piston provide means for tilting the cutter support to vary the inclination of the kerf cutter with respect to the horizontal. For supplying fluid under pressure to the lift cylinders 25 for the arm structure and the cutter support tilting and locking cylinder 71, there is provided a bevel gear 74 meshing with and driven by the bevel gear 35 and having its hub suitably journaled within the machine frame. The hub of this bevel gear is keyed to the shaft 75 of a pump 16 herein arranged within a chamber 77 formed within the machine frame for containing a supply of fluid. This pump is adapted to supply fluid under pressure through suitable valve controlled pipe connections to the cylinders to effect reciprocation of the pistons and for locking the pistons within their respective cylinders. Obviously such valve and piping connections may assume various forms such as a four-way valve controlling communication between a supply connection from the pump and a discharge line to the fluid chamber and connections to the cylinders; and a suitably loaded by-pass to discharge in the fluid chamber.

The driving mechanism for the feeding and controlling drums 6 and 7 for rotating the latter in a direction to wind in their respective cables may be similar to that disclosed in my copending application Ser. No. 699,024, filed Nov. 21, 1933, now matured into Patent No. 2,091,985, granted Sept. 7, 1937, and herein comprises a spur pinion 80 keyed to the rear end of the motor power shaft 16 (see Fig. 7) and meshing with a spur gear 81 keyed to a horizontal shaft 82 herein

extending longitudinally of the machine and suitably journaled within the machine frame. Keyed to the longitudinal shaft 82 is a worm 83 meshing at its opposite sides with, and driving in opposite directions, horizontal worm wheels 84 and 85, herein arranged on parallel vertical axes at opposite sides of the central longitudinal vertical plane of the machine in the manner shown in Fig. 9. The worm wheel 84 is connectible by a multiple disc clutch 86 to a vertical shaft 87 suitably journaled within the machine frame and having fixed thereto and driven thereby a slow speed worm 88 meshing with a slow speed worm wheel 89. The worm wheel 89 is rotatably mounted on a horizontal drum drive shaft 90 arranged transversely of the machine frame with its axis alined with the drum axes and suitably journaled within bearings carried by the opposite side walls of the machine frame. The worm wheel 85 is fixed to a vertical shaft 91 similar to the shaft 87 and likewise journaled within the machine frame, and has fixed thereto and driven thereby a high speed worm 92 meshing with a high speed worm wheel 93 coaxial with the worm wheel 89 and likewise rotatably mounted on the shaft 90, as shown in Fig. 8. The vertical shafts 87 and 91 are arranged with their axes lying in a transverse vertical plane to the rear of the transverse shaft 90, as shown in Fig. 7.

The slow and high speed worm wheels 89 and 93 are connectible to the shaft 90 to effect drive of the latter at either a slow or a high speed, and the means for connecting these worm wheels to the shaft comprise locking plungers 94, herein in the form of balls, controlled by a reciprocable shipper member 95 surrounding the shaft 90 and slidably mounted on the worm wheel hubs. These locking plungers are guided within radial guide slots 96 formed in the hubs of the worm wheels, and are movable into interlocking engagement with locking recesses or grooves 97 formed on the shaft 90. The clutch member 95 is operated by a shipper yoke 98 formed on a longitudinally extending operating rod 99 rotatably mounted within the upper portion of the machine frame and having fixed thereto at its rear end an operating lever 100. This operating lever carries a plunger lock for holding the clutch member 95 in its different positions. It will thus be seen that when the member 95 is shifted toward the left in Fig. 8, the right hand locking plungers 94 are released from the locking grooves on the shaft while the left hand plungers 94 are protruded inwardly within the locking grooves 97, thereby to connect positively the worm wheel to the shaft. When the clutch member is shifted toward the right in Fig. 8, the left hand locking plungers are released while the other worm wheel is connected to the shaft by the right hand locking plungers 94.

The drums 6 and 7 are journaled on the projecting ends of the drum drive shaft 90 at the opposite sides of the feed frame and are connectible in driving relation with the shaft 90 by multiple disc clutches 101 arranged within the drums respectively. The operating means for the disc clutch within the drum 6 comprises an operating rod 102 threaded within a nut 103 secured to the drum and engaging through a ball bearing pressure plate 104 the clutch operating levers 105. The operating means for the clutch within the drum 7 comprises an operating rod 106 extending centrally through a bore formed in the shaft 90 and similarly connected through a ball bearing pressure plate and clutch applying levers to the clutch. Operating rod 102 has a hand

wheel 107, while the operating rod 106 has a hand wheel 108, the hand wheels arranged in coaxial relation. It will thus be seen that by operating these hand wheels the disc clutches for the drums 6 and 7 may be independently or simultaneously applied, as desired. Although the worm wheels 84 and 85 rotate in opposite directions, the worm wheels 89 and 93 are driven in the same direction because the worms 88 and 92 have oppositely inclined teeth, and as a result the drums 6 and 7 are rotated in the same direction at either a slow or a high speed under the control of the interlocking plungers and the drum clutches.

The improved operating mechanism for the low speed clutch 86 for effecting drive of the drum drive shaft 90 at variable speeds through the low speed worm gearing comprises, as shown most clearly in Figs. 9, 10 and 11, a cam element 110 formed integral with the hub of the fast speed worm wheel 93 and having a plurality, herein four, of cam projections 111; and cooperating with the cam surfaces of this cam element is a horizontal longitudinally disposed plunger, herein in the form of a rod 112, guided within a bore formed in a bracket member secured to the machine frame. The rearward end of this plunger rod 112 is formed with a cylindrical enlargement 113 presenting a shoulder 114, and a coil spring 115 encircling the rod is compressed between an adjustable abutment, herein a nut 116 threaded on the rod, and a washer 117 slidably mounted on the rod and normally engaging the shoulder 114. The cylindrical enlargement 113 of the rod passes through and guides a trunnion device 118, herein comprising trunnion blocks 119, 119 having concave recesses 120 slidably engaging the cylindrical sides of the rod enlargement 113 and pivotally connected at 121 to vertically swingable lever arms 122, 122. The trunnion device is supported by the lever arms 122, and these lever arms are supported for pivotal movement on a horizontal pin 123 supported by an adjustable member 124, this adjustable member providing an adjustable fulcrum mounting for the lever arms. The ends of the lever arms opposite from the trunnion device are pivotally connected to a horizontal pin 125 carried by a lever 126 having an elongated sleeve-like hub 127 rotatably mounted on a transverse rod 128 suitably supported within the sides of the machine frame. The end of the sleeve-like hub opposite from the lever 126 has secured thereto a clutch shipper yoke 129 engaging a ball bearing clutch operating member 130. This clutch operating member has projections 131 engageable with the pressure plate 132 of the disc clutch 86. In the present construction the lever fulcrum adjusting member 124 is in the form of an eye-bolt having a threaded portion 133 threadedly engaged within a rotatable nut member 134 in turn threadedly connected at 135 within the rear end wall of the machine frame and having an operating handle 136. The threads on the threaded portion 133 and the nut member 134 are respectively right and left hand, and upon rotation of the hand wheel 136 the member 124 is moved axially to vary the position of the fulcrum of the lever arms 122. It will thus be seen that when the parts are in the position shown in Fig. 11, and the cam element 110 is rotating, the cam projections 111 engaging the plunger rod 112 move the latter axially, increasing the tension of the spring 115 and, through the spring, washer 117 and trunnion device, effecting swinging of the lever arms 122, thereby to swing the lever 126, and, as a result, depressing the shipper yoke

129 to effect intermittent application of the friction clutch 86, the clutch being applied every time a cam projection acts to move the plunger rod 112 to the right, and the clutch being released each time the plunger rod engages a low point in the cam. By adjusting the handle 136 the position of the fulcrum of the lever arms 122 may be changed to vary the time intervals of application of the friction clutch. By moving the lever fulcrum into its extreme inner position, the inner end of the plunger rod is at all times held against the surface of the cam element, thereby effecting constant application of the friction clutch, the spring 115 compressing as the cam projections engage and move the plunger rod. By moving the lever fulcrum to its extreme opposite position, the cam element may rotate while the friction clutch is at all times released, the plunger rod moving axially back and forth as the cam projections engage the same without applying the clutch. It will thus be seen that the slow speed worm gearing 88, 89 may be driven through the disc clutch 86 at any desired slow feeding speed between zero and a predetermined maximum slow feeding speed, the worm gearing being driven intermittently through a wide range of speeds between said maximum low speed and zero and continuously at said maximum low speed. It will also be evident that when the disc clutches within the cable drums 6 and 7 are applied and the high speed worm wheel 93 is connected to the drum drive shaft 90 by the interlocking clutch device 94, 97, the drums may be rotated in winding direction at a relatively high machine moving or haulage speed; while when the disc clutch 86 is applied and the low speed worm wheel 89 is connected to the shaft 90 by the interlocking clutch mechanism, the drums may be driven in winding direction at a relatively low feeding speed; and by varying the application of the disc clutch 86, the drums may be driven in winding direction at any desired low feeding speed between zero and the maximum low feeding speed. As previously mentioned, the drums may be simultaneously connected to the drum drive shaft 90 or one or the other may be released therefrom, as desired; it also being possible to release both drums from the shaft. By moving the shipper member 98 into an intermediate or neutral position shown, both of the interlocking clutch mechanisms are released, thereby permitting the drum drive shaft 90 to remain stationary while the worm wheels 89 and 93 both rotate.

The mining machine above described is adapted to be supported on a transport truck during transport of the machine about the mine as is usual in room and pillar machines, and the wheels of the transport truck may be driven from the mining machine motor through the spur pinion 80, spur gear 81, the longitudinal drive shaft 82, the rear end of this shaft being polygonally formed at 140 (see Fig. 7) for engagement within a polygonal socket formed on the driving element of the truck.

In the modification shown in Figs. 12, 13 and 14, the cutter support 4 of the preferred embodiment of the invention above described is omitted and there is tiltably mounted on the outer extremity of the arm structure 3 for rocking movement with respect thereto about a transverse axis parallel with the arm structure pivot axis a support 141 having lateral trunnions 142, 142 journaled within the forward extremities of the side arm portions of the arm structure. Journaled in sleeve bearings 143 supported within a

cylindrical bearing portion 144 of the tilting support 141 is an elongated sleeve-like neck frame 145 of a rotatable cutter head 146, the head axis being arranged at right angles to the pivotal axis of the tiltable frame 141 and extending substantially longitudinally of the machine. Journaled in the frame of the cutter head 146 and the tilting support 141 and arranged with its axis alined with the cutter head axis is a shaft 147 having keyed thereto at its rear end a bevel gear 148 meshing with and driven by a bevel gear 149 keyed to the shaft 46 and driven through the chain and sprocket connection 42, 43, 45 arranged within the hollow side arm portion 18 of the arm structure. Keyed to the forward end of the shaft 147 is a bevel gear 150 meshing with the bevel gear 48 for driving the cutter chain drive sprocket 51. In this instance the cutter bar 53 is mounted on a hanger 151 having a cylindrical portion 152 rotatably mounted on a cylindrical bearing portion 153 formed integral with the cutter head frame. The cylindrical portion 152 has a radial flange 154 with which cooperates a retaining ring 155 bolted to the cutter head frame for maintaining the hanger frame 151 in its swiveled position on the cutter head frame. It will thus be seen that the cutter bar is pivotally mounted for swinging movement with respect to the cutter head frame about an axis coincident with the axis of the drive shaft 50 for the cutter chain sprocket 51 and is adapted to be locked in its different angular positions of adjustment by a locking pin 156 arranged in a bore formed on the cutter head frame and adapted to register with any one of a series of locking apertures 157 formed in the flange 154 of the bar hanger frame. The means for rotating the neck frame 145 of the cutter head within its bearings with respect to the tiltable support 141 comprises a fluid pressure motor 158 having its casing secured to the tiltable support 141, and the drive shaft 159 of this motor has fixed thereto a worm 160 meshing with a worm wheel 161 herein formed integral with the neck frame 145. It will thus be seen that the kerf cutter may be adjusted about the head axis into horizontal and vertical cutting positions and that by swinging the arm structure and support 141 about their respective pivots the elevation and angular position of the head axis may be varied as desired. The "parallel motion" chain, as in the form of the invention above described, maintains automatically the cutter head axis always in a horizontal position during swinging of the arm structure and by operating the tilting cylinder for this chain the head axis may be tilted with respect to the horizontal. Otherwise this form of the invention is the same as that above described.

The operation of the forms of the improved mining machine above described will be clearly apparent from the description given. When the kerf cutter is in the position shown in Figs. 2 and 13, the hydraulic cylinders 25 may be operated to depress the arm structure 3 to lower the kerf cutter into a bottom cutting position at the level of the mine floor. When the kerf cutter is thus disposed the clutch 38 may be connected to effect rapid circulation of the cutter chain about the margin of the cutter bar, and the feed cable 8 may be extended from the feed drum 6 around the guide sheaves 13, 14 at the advancing side of the machine to a suitable anchor jack located at the coal face in advance of the machine while the controlling cable 9 may be extended from the control drum 7 around the guide sheaves 12

and 10 to a suitable anchor jack located at the rib, and as the cables are wound in by the drums, the machine is slid in a longitudinal direction bodily over the mine floor to sump the kerf cutter within the coal seam. Upon completion of the sumping cut, the feed cable 8 is extended from the guide sheave 14 at the advancing side of the machine transversely across the coal face to an anchor jack located at the left hand rib, and as the feed cable 8 is wound in by the drum 6, the mining machine is slid bodily laterally over the mine floor to cut a horizontal kerf transversely across the coal face, the controlling drum 7 at that time controlling the angular position of the mining machine with respect to the coal face in a well known manner. By adjustment of the arm structure, the kerf cutter may be positioned to cut horizontal kerfs at different elevations between the mine floor and mine roof, the "parallel motion" mechanism maintaining the kerf cutter in horizontal cutting position during swinging of the arm structure. By operating the tilting cylinder 11 the cutter support 4 may be tilted about its pivot with respect to the arm structure to move the kerf cutter through a wide range of angularly related cutting planes with respect to the horizontal. When it is desired to insert a vertical shear cut in the coal face, the motor 158 may be operated to rotate, through the worm gearing 161, the cutter head 146 into a position wherein the kerf cutter is in a vertical shearing position. The arm structure 3 may then be swung upwardly to position the tip end of the kerf cutter adjacent the mine roof and the machine is then fed bodily longitudinally by the feeding and controlling cables to sump the kerf cutter within the coal. The hydraulic cylinders 25 are then operated to swing the arm structure 3 downwardly about its pivot to move the kerf cutter in an arcuate path about the arm structure pivot to cut a vertical kerf in the coal face between the mine roof and mine floor. The feeding and controlling cables are then operated to move the machine bodily rearwardly from the coal face to withdraw the kerf cutter from the coal seam. By rotating the cutter head 146, the kerf cutter may be disposed in vertical shearing positions at either side of the arm structure and in horizontal cutting position above and below the forward extremity of the arm structure. By rotating the cutter head to move the kerf cutter into a top cutting position and by swinging the arm structure upwardly, the kerf cutter may be positioned to cut a horizontal kerf at the mine roof, and when the kerf cutter is thus disposed the kerf cutter may be sumped in, moved transversely across the coal face and thereafter withdrawn from the coal, in the manner above described.

In the modified form of construction in Figs. 15 to 19 inclusive, there is shown a mining machine of the track supported and guided type comprising a truck frame 165 mounted on truck wheels 166 supported and guided by track rails 167 laid on the mine floor. Supported on the truck frame is a machine frame 168, generally similar to the machine frame of the forms of the invention above described, having mounted thereon a vertically swingable arm structure 169 similar to the arm structure 3 and similarly straddling the forward portion of the machine frame. Supported by the forward portion of the machine frame is a motor 170 having its power shaft 171 horizontally disposed and extending longitudinally of the machine. The ver-

tically swinging arm structure 169 has parallel side arm portions 172 and 173 extending longitudinally along the sides of the motor casing at the opposite sides of the machine frame, and the 5 rear ends of these side arm portions have cylindrical bearing portions 174 journaled on bearing sleeves supported by trunnions 175 projecting laterally from the opposite sides of the machine frame. It will thus be seen that the arm 10 structure is swingable vertically with respect to the machine frame about a horizontal axis extending transversely of the machine and located at the rear of the motor above the truck frame 165 as shown in Fig. 18. Rigidly fixed to and 15 extending between the forward extremities of the side arm portions of the arm structure is a connecting frame 176 having rigidly fixed thereto a vertical kerf cutter 177. Keyed to the motor power shaft 171 is a bevel gear 178 meshing with 20 a bevel gear 179 keyed to a horizontal shaft 180, similar to the shaft 37 of the forms of the invention above described, and similarly connectible by a sliding gear clutch 181 to a shaft 182. The alined shafts 181, 182 are suitably journaled 25 within the machine frame and are arranged with their axes alined with the pivotal axis of the arm structure. Keyed to the outer end of the shaft 182 is a chain sprocket 183 connected to an endless chain 184, the arm 173 being made 30 hollow to receive the chain, and this chain engages and drives a chain sprocket 185 keyed to a shaft 186 journaled in the connecting frame 176. Formed on and rotatable with the shaft 186 is a spur gear 187 meshing with a spur gear 188 keyed to a shaft 189 herein arranged parallel 35 with the shaft 186 and likewise journaled in the connecting frame 176. Keyed to and driven by the shaft 189 is a chain sprocket 190 which engages and drives an endless cutter chain 191 40 mounted for circulation about the margin of an elongated vertical plane cutter bar 192, the latter herein fixed by bolts 193 to the connecting frame 176. The means for elevating and depressing the arm structure to swing the kerf cutter 45 vertically in its plane comprises, as in the forms of the invention above described, a pair of hydraulic cylinders 194 arranged at the opposite sides of the machine frame between the frame and arm structure beneath the side arm portions 50 of the latter, and these cylinders are each pivotally mounted to swing in vertical planes about a horizontal pivot at 195. Each of the cylinders contains a reciprocable piston 196 having an upwardly extending piston rod 197 extending 55 through the packed upper head 198 of the cylinder and these piston rods are pivotally connected at 199 within depending lugs 200 formed integral with the arm structure side arm portions. It will thus be seen that when fluid pressure is 60 supplied to the cylinders 194 the arm structure may be swung upwardly and downwardly about its pivot and may be locked in any adjusted position by trapping the fluid within the cylinders. As in the forms of the invention above described, 65 a pump 201 driven by a bevel gear 202 meshing with the bevel gear 178 is provided for supplying fluid under pressure to the hydraulic cylinders.

Now referring to the improved propelling mechanism for the machine, it will be noted that 70 keyed to the rear end of the motor power shaft 171 is a spur pinion 204 meshing with a spur gear 205 keyed to a longitudinally extending shaft 206. Fixed to and driven by the shaft 206 75 is a worm 207 meshing at its opposite sides with

worm wheels 208 and 209 herein arranged on parallel vertical axes in a manner similar to the worm wheels 84 and 85 of the forms of the invention above described. These worm wheels are connectible by multiple disc clutches 210 to parallel vertical shafts 211 and 212 respectively. Fixed to these shafts are low speed worms 213 and 214 having teeth of the same inclination. As the worm wheels 208, 209 are driven by the worm 207 in opposite directions, the worms 213 and 214 10 are rotated in opposite directions, and since they have teeth of the same inclination they effect drive of low speed worm wheels 215 and 216 meshing therewith in opposite directions at the same low speed. The clutches 210 are each operated by a bell crank lever 217 pivotally supported by a transverse rod 218 and engaging a ball bearing clutch applying member 219. Each lever is operated by a pressure screw 220 having a manual operating handle 221. It will thus be 15 seen that the disc clutches 210 for controlling the connection of the worm wheels 208, 209 to the vertical shafts may be independently manually controlled. The relatively reversely rotating low speed worm wheels 215, 216 are rotatably mounted 20 on a horizontal drive shaft 222 (see Fig. 16) suitably journaled at its ends within bearings supported by the sides of the machine frame. As in the forms of the invention above described, the worm wheels 215, 216 are connectible to the 25 shaft 222 by means of an interlocking clutch mechanism 223 and having similar operating means. Journaled within bearing sleeves supported within the shaft 222 and extending centrally through the latter is a shaft 224, and the 30 shafts 222, 224 are connectible in driving relation by means of a disc clutch 225 having operating means 226 controlled by a hand wheel 227. Keyed to the end of the shaft 224 remote from the clutch 225 is a chain sprocket 228 which is 35 connected by an endless chain 229 to a chain sprocket 230 journaled on a bearing sleeve supported by a horizontal shaft 231. The shaft 231 extends transversely of the machine and is journaled at its opposite ends within bearings supported within brackets carried by the sides of the 40 truck frame. The hub of the sprocket 230 is connectible by a sliding clutch 232 to the shaft 231. Keyed to the opposite end of the shaft 231 is a chain sprocket 233 connected by an endless chain 234 to a chain sprocket 235 fixed to the rear truck wheel axle. The front and rear truck wheel axles are connected in driving relation by means of a chain and sprocket connection 236. It will thus be seen that when the sprocket 230 is connected by the clutch 232 to the shaft 231 and one or the other of the disc 45 clutches 210 is applied, the mining machine may be propelled bodily along the mine trackway either forwardly or rearwardly at a relatively low cutting speed.

The high speed propelling means for the machine comprises a shaft 237 journaled in a gear housing 238 supported on the rearward portion of the truck frame at the rear of the machine frame, and connected by a coupling 239 to the shaft 206, as shown in Fig. 19. Keyed to the rear end of the shaft 237 is a bevel gear 240 meshing with reversely rotating bevel gears 241 and 242 suitably journaled within the gear housing 238. Disc clutches 243 and 244 respectively are provided for selectively connecting the reverse bevels 241, 242 to a tubular shaft 245 suitably journaled within the gear housing 238 and through which the shaft 231 centrally extends. Clutch operat- 50 55 60 65 70 75 80 85 90 95 98

ing means including a clutch shipper member 246 having an operating lever 247 is provided for effecting application of the clutches 243, 244. As shown in Fig. 15, the tubular shaft 245 is connectible to the shaft 231 by means of the sliding clutch 232. It will thus be seen that when the shaft 231 is connected by the clutch 232 to the shaft 245 and one or the other of the disc clutches 243, 244 is applied, the apparatus may be propelled along the mine trackway either forwardly or rearwardly at a relatively high transport speed.

The operation of the modified form of the invention shown in Figs. 15 to 19, inclusive, is as follows: The trackway 167 is laid perpendicular to the coal face, and when it is desired to insert a vertical shear cut in the coal seam, fluid pressure is supplied to the hydraulic cylinders 194 to effect swinging of the arm structure 169 upwardly in a vertical direction about its pivot to move the tip end of the kerf cutter adjacent the mine roof. The clutch 181 is then shifted to connect the shafts 180, 182 and as a result, the cutter chain is rapidly circulated about the margin of the cutter bar by the motor 170 through the chain and sprocket connection 183, 184 and 185 and spur gearing 187, 188. The low speed clutch 210 controlling the connection of the vertical shaft 211 to the worm wheel 208 may then be applied, and as a result, the mining machine is propelled forwardly along the mine trackway at a low cutting speed to sump the kerf cutter within the coal seam. Upon the completion of the summing cut, hydraulic pressure is supplied to the cylinders 194 to swing the arm structure downwardly about its pivot to move the kerf cutter in an arcuate path about the arm structure pivot to cut a vertical kerf between the mine roof and mine floor. When the swinging cut is completed, the clutch controlling the low speed clutch 210 for connecting the vertical shaft 212 for the worm wheel 209 is applied, and as a result, the mining machine is propelled rearwardly along the mine trackway at a low cutting speed to withdraw the kerf cutter from the coal. The mining machine may be propelled at a high speed along the mine trackway under the control of the disc clutches 243, 244, the clutch 232 at that time being released from the sprocket 230 and the shaft 231 connected to the shaft 245. As in the form of the invention shown in Figs. 1 and 2, the arm structure 169 may be provided with the rotating cutter head shown in Figs. 12 and 13 to enable the machine to operate as a horizontal "slabbing" cutter with the kerf cutter projecting laterally in a right angle position from the side of the machine.

As a result of this invention, it will be noted that an improved mining machine is provided having an improved adjustable supporting structure for the kerf cutting mechanism whereby the kerf cutter may be adjusted and operated in an improved manner. It will further be noted that an improved adjustable arm structure is provided having associated therewith improved "parallel motion" means whereby when the kerf cutter is adjusted into different elevated positions the kerf cutter is always automatically maintained horizontal, and having embodied therein improved means for tilting the kerf cutter through a wide range of angularly related cutting planes with respect to the horizontal. It will also be evident that improved means for driving and feeding the kerf cutter are provided. These and other uses and advantages of the im-

proved mining machine will be clearly apparent to those skilled in the art.

While there are in this application specifically described three forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a mining machine, a machine frame, an elongated rigid arm structure pivotally mounted on said frame to swing in a vertical direction with respect thereto and having parallel side arm portions straddling and extending longitudinally along the sides of the forward portion of the machine frame and pivotally mounted on the latter on aligned horizontal axes located a substantial distance to the rear of the forward end of said frame, one of said side arm portions being hollow, and a transverse frame portion extending horizontally between the forward extremities of said side arm portions and located in advance of said frame, a kerf cutter mounted on said transverse frame centrally between the side arm portions of said arm structure, and motor operated means for driving said kerf cutter including a chain sprocket coaxial with the arm structure pivot, a chain sprocket operatively connected to the kerf cutter and arranged with its axis parallel with the axis of said first mentioned chain sprocket, and an endless drive chain engaging said chain sprockets and housed within said hollow side arm portion.

2. In a mining machine, a machine frame, an elongated rigid arm structure pivotally mounted on said frame to swing in a vertical direction with respect thereto and having parallel side arm portions straddling and extending longitudinally along the sides of the forward portion of the machine frame and pivotally mounted on the latter on aligned horizontal axes located a substantial distance to the rear of the forward end of said frame, one of said side arm portions being hollow, and a transverse frame portion extending horizontally between the forward extremities of said side arm portions and located in advance of said frame, a kerf cutter mounted on said transverse frame centrally between the side arm portions of said arm structure, motor operated means for driving said kerf cutter including a chain sprocket coaxial with the arm structure pivot, a chain sprocket operatively connected to the kerf cutter and arranged with its axis parallel with the axis of said first mentioned chain sprocket, and an endless drive chain engaging said chain sprockets and housed within said hollow side arm portion, and devices arranged between said frame and the side arm portions of said arm structure beneath said side arm portions for vertically swinging said arm structure relative to said frame to vary the elevation of the kerf cutter.

3. In a mining machine, a machine frame, an elongated rigid arm structure pivotally mounted on said frame to swing in a vertical direction with respect thereto and having parallel side arm portions straddling the forward portion of the machine frame, said side arm portions being hollow, a kerf cutter mounted at the outer extremity of said arm structure, motor operated means for driving said kerf cutter including transmission connections housed within one of

- said hollow arm portions, and means for always automatically maintaining said kerf cutter parallel to a common straight line during swinging of said arm structure including parallel motion connections housed within said other side arm portion.
4. In a mining machine, a machine frame, an arm structure pivotally mounted on said machine frame to swing relative thereto, a cutter support pivotally mounted on the outer extremity of said arm structure to swing relative thereto about an axis parallel with the arm structure pivot axis, a kerf cutter carried by said swingable support, means for swinging said arm structure, and means for maintaining automatically said kerf cutter always parallel to a common straight line during swinging of the arm structure including a chain sprocket fixed to said support in coaxial relation with the support pivot, a sprocket in coaxial relation with the arm structure pivot, an endless chain extending between and engaging said sprockets, and means for holding said last mentioned sprocket against rotation relative to said machine frame.
5. In a mining machine, a machine frame, an arm structure pivotally mounted on said machine frame to swing relative thereto, a cutter support pivotally mounted on the outer extremity of said arm structure to swing relative thereto about an axis parallel with the arm structure pivot axis, a kerf cutter carried by said swingable support, means for swinging said arm structure, means for maintaining automatically said kerf cutter always parallel to a common straight line during swinging of the arm structure including a chain sprocket fixed to said support in coaxial relation with the support pivot, a sprocket in coaxial relation with the arm structure pivot, an endless chain extending between and engaging said sprockets and means for holding said last mentioned sprocket against rotation relative to said machine frame to effect tilting through said chain and sprocket connection of said cutter support relative to said arm structure to move said kerf cutter into angularly related cutting planes with respect to said straight line.
6. In a mining machine, a machine frame, an arm structure pivotally mounted on said machine frame to swing with respect thereto, a cutter support pivotally mounted on the outer extremity of said arm structure to swing with respect thereto about an axis parallel to the arm structure pivot axis, a kerf cutter carried by said cutter support, and means for tilting said cutter support relative to said arm structure to move said kerf cutter into angularly related cutting planes including a sprocket fixed to said cutter support in coaxial relation with the support pivot, a sprocket in coaxial relation with the arm structure pivot, an endless chain extending between said sprockets and engaging the same, and means for rotating said last mentioned sprocket.
7. In a mining machine, a machine frame, an elongated rigid arm structure pivotally mounted on said frame on a horizontal axis to swing in a vertical direction with respect thereto, a cutter support pivotally mounted at the outer extremity of said arm structure to swing with respect thereto about an axis parallel with the arm structure pivot axis, a kerf cutter carried by said cutter support, means for swinging said arm structure about its pivot, parallel motion means connected to said cutter support and said frame and extending therewith for maintaining automatically said kerf cutter always parallel to a common straight line during swinging of said arm structure, said parallel motion means including connections mounted on said arm structure to swing therewith, and means associated with an element of said parallel motion means for tilting said cutter support about its pivot relative to said arm structure to move said kerf cutter into angularly related cutting planes with respect to said straight line, said tilting means including means for moving said parallel motion connections relative to said arm structure to effect cutter support tilt while the arm structure remains stationary.
8. In a mining machine, a machine frame adapted to rest upon and slide in any direction over the mine floor, flexible feeding means for feeding the machine frame over the mine floor, an elongated rigid arm structure pivotally mounted on said frame on a horizontal axis to swing in a vertical direction with respect thereto, a cutter support pivotally mounted at the outer extremity of said arm structure to swing with respect thereto about an axis parallel with the arm structure pivot axis, a kerf cutter carried by said swingable cutter support and tilttable with the latter into relatively inclined cutting planes, and means for swinging said cutter support about its pivot relative to said arm structure including connections mounted on said arm structure and movable relative thereto to effect support tilt while said arm structure remains stationary as regards swinging movement relative to said frame, and means on said machine frame and relative to which said arm structure is swingable for moving said connections relative to said arm structure.
9. In a mining machine, a portable base, but a single unitary arm structure pivotally mounted on said base to swing in a vertical direction with respect thereto on a horizontal axis, a horizontal kerf cutter mounted on the outer extremity of said arm structure to swing relative thereto about a horizontal axis parallel to said arm structure pivot axis, means for swinging said arm structure to vary the elevation of said kerf cutter, means connected between said base and said kerf cutter for automatically holding the latter in a horizontal cutting position during swinging of said arm structure and including an element on said frame, an element connected to said kerf cutter and a connection between said elements, said connection mounted on said arm structure to swing therewith and between which and said arm structure relative movement occurs during arm structure swing, and means connected to one of said elements for tilting said kerf cutter relative to said arm structure into cutting planes inclined with respect to the horizontal.
10. In a mining machine, a portable base, but a single unitary arm structure pivotally mounted on said base to swing in a vertical direction with respect thereto on a horizontal axis, a horizontal kerf cutter mounted on the outer extremity of said arm structure to swing relative thereto about a horizontal axis parallel to said arm structure pivot axis, means for swinging said arm structure to vary the elevation of said kerf cutter, means connected between said base and said kerf cutter for automatically holding the latter in a horizontal cutting position during swinging of said arm structure and including an element on said frame, an element connected to said kerf cutter and a connection between said elements, said connection mounted on said arm structure to swing therewith and between which and said arm structure relative movement occurs during arm structure swing, and means connected to one of said elements for tilting said kerf cutter relative to said arm structure into cutting planes inclined with respect to the horizontal.

structure relative movement occurs during arm structure swing, and means connected to one of said elements for moving said connection relative to said arm structure to tilt said kerf cutter relative to said arm structure into cutting planes inclined with respect to the horizontal.

5 11. In a mining machine, a portable base, but a single unitary arm structure pivotally mounted on said base to swing in a vertical direction with respect thereto on a horizontal axis, a horizontal kerf cutter mounted on the outer extremity of said arm structure to swing relative thereto about a horizontal axis parallel to said arm structure pivot axis, means for swinging said arm structure to vary the elevation of said kerf cutter, means connected between said base and said kerf cutter for automatically holding the latter in a horizontal cutting position during swinging of said arm structure including an element on said frame, an 15 element connected to said kerf cutter and a connection between said elements, and a hydraulic ram connected to one of said elements for moving said connection relative to said arm structure to tilt said kerf cutter relative to said arm structure into cutting planes inclined with respect to the horizontal.

20 12. In a mining machine, a portable base, an arm structure pivotally mounted on said base to swing in a vertical direction with respect thereto, a horizontal kerf cutter mounted on the outer extremity of said arm structure to swing into relatively inclined cutting planes with respect thereto about an axis parallel with the arm structure pivot axis, and motor operated means for 25

moving said kerf cutter about said parallel pivot into cutting planes inclined with respect to the horizontal including a servo-motor on said base and relative to which said arm structure is swingable, and connections between said servo-motor and said kerf cutter and movable relative to said arm structure while the latter remains stationary as regards swinging movement about its pivot relative to the base, said servo-motor exclusively for controlling said connections and said connections alternatively actuated and held by said servo-motor.

10 13. In a mining machine, a portable base, an arm structure pivotally mounted on said base to swing in a vertical direction with respect thereto, a horizontal kerf cutter mounted on the outer extremity of said arm structure to swing into relatively inclined cutting planes with respect thereto about an axis parallel with the arm structure pivot axis, and motor operated means for 20 moving said kerf cutter about said parallel pivot into cutting planes inclined with respect to the horizontal axis including a power device on said base, and connections movable relative to said arm structure while the latter remains stationary 25 as regards swinging movement about its pivot relative to the base, said connections actuated by said power device and including a member aligned with the arm structure pivot axis, a member aligned with the cutter pivot axis, and a transmission member extending between and connecting said members.

MORRIS P. HOLMES.
